TOWEL DISPENSING DEVICE

Leo M. Harvey, Los Angeles, Calif.

Application October 5, 1934, Serial No. 746,984

21 Claims.

(Cl. 312—38)

This invention relates to a towel dispensing device or towel cabinet and a general object of the invention is to provide a practical, effective cabinet for dispensing paper toweling that is sanitary and convenient to operate.

The towel cabinets that have been introduced having means for governing the withdrawal of toweling usually include levers, handles, buttons or the like that must be engaged and operated by the users in order to withdraw the toweling. The hands of the persons using the cabinets are often wet and the operating levers, handles and buttons, as well as the adjacent parts of the cabinets, soon become soiled and unsanitary. The towels or toweling can be withdrawn from many of the towel cabinets now in use in unlimited quantities by merely repeatedly operating the controls or by maintaining a pull on the toweling. Persons using such towel cabinets often withdraw toweling greatly in excess of their actual needs and quickly deplete the supplies of toweling in the cabinets.

Another object of the present invention is to provide a towel cabinet in which the toweling may be easily and conveniently withdrawn for use without directly manually engaging or actuating handles, levers, buttons or other mechanical parts.

Another object of the invention is to provide a towel cabinet that includes a mechanism governing the withdrawal of toweling from the case that may be easily released and actuated through the medium of a portion of the toweling accessible through an opening in the case, said portion of toweling being receivable by the person who engages it.

Another object of the invention is to provide a towel cabinet of the character mentioned that conceals and prevents the user from engaging the lower edge portion of the toweling until the control mechanism has been released or actuated as set forth above.

Another object of the invention is to provide a towel cabinet in which the predetermined or given length of toweling that may be withdrawn from the case following the release or actuation of the control must be cut or torn free before the control may again be released or actuated to allow the withdrawal of another length of toweling. The control of the device is such that only a given length of toweling may be withdrawn from the case at each operation of the device and requires that the user cut or tear free said portion of toweling and then manually reactivate the control before a second portion of toweling

may be withdrawn, which series of manual acts or operations usually deters the user from withdrawing excessive or unneeded quantities of toweling.

Another object of the invention is to provide the combination of a novel continuous supply of paper toweling provided with spaced series of openings and a cabinet or dispensing device for handling said supply, including a mechanism which cooperates with the openings to limit the withdrawal of the toweling.

Another object of the invention is to provide a continuous supply of paper toweling provided with spaced sets or series of openings which cooperate with the control mechanism of a towel cabinet and provided with cuts, slits or series of perforations adjacent said openings whereby the toweling may be cut or torn free at the openings without being torn longitudinally or being otherwise injured.

Another object of the invention is to provide a towel cabinet that is compact and inexpensive and does not involve a towel feeding mechanism or the towel guiding and supporting rolls and shafts usually necessary where towel feeding mechanisms are employed.

Another object of the invention is to provide a towel cabinet of the character mentioned that is substantially tamper proof and incapable of improper operation.

Another object of the invention is to provide a towel cabinet of the character mentioned that includes means for engaging the toweling along the line where it is to be cut or torn free to insure the proper cutting or tearing of the paper toweling which means is released from the toweling during its withdrawal so that it does not interfere with the proper withdrawal of the toweling.

Another object of the invention is to provide a towel cabinet of the character mentioned in which the portion of toweling that is engageable to release the control is supported and backed by a guide element that is operatively connected with the control and manually movable through the medium of the toweling to release the control.

The various objects and features of my invention will be fully understood from the following detailed description of a typical preferred form and application of the invention, throughout which description reference is made to the accompanying drawings, in which:

Fig. 1 is a front elevation of the towel cabinet provided by the invention. Fig. 2 is an end or

side elevation of the cabinet. Fig. 3 is an enlarged vertical detailed sectional view taken substantially as indicated by line 3-3 on Fig. 1 illustrating the parts of the control in their normal or unactuated positions. Fig. 4 is a view similar to Fig. 3 showing the parts of the control in the positions they assume after the manual actuation or release. Fig. 5 is a view similar to Fig. 3 illustrating the parts in the positions they assume during the withdrawal of the toweling from the case. Fig. 6 is a vertical detailed sectional view taken substantially as indicated by line 6-6 on Fig. 5 with the outline of one of the guides appearing in broken lines, and Fig. 7 is an enlarged fragmentary horizontal sectional view taken as indicated by line 7-7 on Fig. 6.

The toweling cabinet of the present invention includes generally: a case 10; a supply 11 of toweling in the case 10; and a control C governing the withdrawal of the toweling from the case, comprising a movable element 12 over which a portion of the toweling T is trained, means 13 normally preventing the withdrawal of toweling and for limiting the withdrawal of toweling, releasable by manual actuation of the element 12, and means 14 for preventing the actuation or release of the means 13 releasable by tearing or cutting free the portion of toweling withdrawn from the case 10.

The case 10 is a hollow structure for housing the supply of toweling 11 and the mechanism of the control C. In the particular embodiment of the invention illustrated in the drawings the case 10 is adapted to be mounted or supported on a wall or other vertical support. The case 10 may be substantially rectangular as illustrated in the drawings and may be formed of sheet metal or the like. The housing or case 10 preferably includes two sections, a section A providing a back 15 and a bottom 16 and a section B forming the top 17, the front 18 and the sides 19 of the case. The bottom 16 preferably constitutes the carrier or support for the supply of toweling and is spaced some distance above the lower extremity of the back 15. The major portion of the bottom 16 projects substantially horizontally from the back 15 while its forward portion 20 is inclined upwardly and forwardly. A horizontal shelf or flange 21 is provided on the forward edge or extremity of the bottom 16. The top 17 may be horizontal while the front 18 and the sides 19 may be vertical as illustrated in the drawings. The front 18 and the sides 19 project downwardly beyond the bottom 16 and are of substantially the same vertical extent as the back 15. In accordance with the invention the case section B is hinged or pivoted to the section A to be swung to an open position where the interior of the case is conveniently accessible. In the structure illustrated in the drawings the section B has its sides 19 pivotally connected with the section A at 22 so that the section B may be swung downwardly and forwardly relative to the section A.

The case 10 is provided with means for carrying the control C and for supporting and positioning the supply 11 of toweling. As described above the bottom 16 of the section A carries or supports the supply 11 and partitions or plates 24 are vertically disposed at the opposite ends of the bottom 16 to retain the towel supply in its proper position on the bottom. The plates 24 may be suitably attached to the back 15 and bottom 16. In the preferred construction the plates 24 project downwardly beyond the bot-

tom 16 and are spaced inwardly from the sides 19 to leave spaces for housing certain parts of the control C. Outwardly projecting flanges 26 may be provided on the lower ends of the plates 24 to close the lower ends of these spaces. The upper extremities or edges of the plates 24 are inclined downwardly and forwardly and have outwardly or laterally extending lips 27 to facilitate the easy positioning of the supply 11 between the plates. The forward edges of the plates 24 have upwardly and rearwardly inclined portions 28 forming stops for limiting the inward movement of the element 12 as will be herein-after described.

In accordance with the invention the front 18 of the case has an opening 29 spaced between its upper and lower extremities and an opening 30 extending upwardly from its lower end. The opening 29 is provided to render the toweling on the element 12 accessible for engagement by the user whereby he may actuate the element to release the control C. The opening 30 is preferably in the nature of a comparatively large notch in the lower end of the front 18 and is provided to make the lower edge portion of the toweling T accessible for engagement by the user after the release of the means 13 of the control C. The opening 29 may be round while the opening 30 may have a rounded upper wall and downwardly and laterally divergent side walls. An inwardly turned lip or rim 31 is provided on the front 18 around the opening 29 to prevent persons from tampering with the element 11 and other parts of the mechanism. A similar inwardly turned flange or lip 32 is provided along the edge of the opening 30.

The supply 11 of toweling is preferably a continuous or uninterrupted length of paper toweling capable of being readily withdrawn from the case 10 under the control of the mechanism C. In the particular combination illustrated in the drawings the supply 11 is in the nature of a continuous roll of paper toweling, it being understood that the invention contemplates the employment of a supply consisting of a continuous strip of folded paper toweling. The toweling T comprising the supply 11 is preferably a long strip of uniform width and where the supply is in the form of a roll the strip is rolled about a spool 32a. The supply roll 11 is supported on the bottom 16 and is held against excessive rolling movement by the back 15 and inclined portion 20 of the bottom. The plates 24 guide the roll 11 and limit its longitudinal movement. It is a feature of the invention that the toweling T of the supply 11 is provided with longitudinally spaced sets or series of openings 33. The longitudinal spacing of the openings 33 along the strip of toweling may be uniform or irregular as desired or found practical. The portions of the toweling T occurring between the series of openings 33 comprise the towels that are withdrawn and torn free by the users of the device.

Each longitudinally spaced series or set of openings may comprise four openings 33 for co-operation with four parts or fingers of the control C. It is to be understood that the number of openings 33 of each series depends upon the particular formation of the control of the cabinet. The openings 33 of each series are in pairs in the opposite longitudinal edge portions of the strip of toweling T. The openings 33 are preferably elongated longitudinally of the strip of toweling and preferably have rounded opposite ends. The parts or fingers of the control C to be hereinafter

described pass through or extend into the openings 33 to limit the withdrawal of the toweling T from the case 10 and when the fingers are in the openings the user must cut or tear free the 5 withdrawn portion of toweling. It has been found desirable to provide the toweling T with transverse perforations or cuts 34 to facilitate the easy tearing of the toweling along transverse lines at the sets of openings 33. In the particu- 10 lar case illustrated in the drawings the cuts or slits 34 are continuous, it being understood that they may be in the nature of spaced series of relatively small scorings or perforations. A com- 15 paratively long cut or slit 34 extends transversely across the toweling between points adjacent the two innermost openings 33 while similar cuts 34 extend between points adjacent the openings 33 of each pair of openings. The cuts or slits 34 are aligned and preferably occur in planes substan- 20 tially tangential to the upper ends of the openings 33. It will be apparent how the provision of the cuts or slits 34 insures the proper straight tearing or cutting of the toweling in or adjacent the planes of the series of openings 33.

25 The control C is an important feature of the invention and includes parts for cooperating with the openings 33 of the toweling and parts for cooperating with the face or body of the toweling to govern the withdrawal of the toweling from 30 the case 10 and to allow the withdrawal of only one length of toweling at each actuation of the device. In accordance with the invention the control C is released to allow the withdrawal of a length of toweling by manually pressing on the 35 toweling T trained over the element 12 to move the element inwardly. The element 12 which comprises a part of the control C is in the nature of a panel, apron, or guide on which the toweling T is trained or arranged for withdrawal through an opening 35 in the lower forward corner portion of the case 10. The element 12 is arranged 40 within the case 10 and is normally substantially vertical and spaced a short distance to the rear of the front 18.

45 The principal section or part of the element 12 may be a substantially rectangular plate 36 provided at its lower end with an opening 37 to oppose or register with the opening 30 in the front of the case. The opening 37 is preferably of the 50 same size and shape as the opening 30. The plate 36 is pivotally supported at its lower end by pivot pins 38 and suitable brackets 39. Vertical or longitudinal spacers 40 are provided along the opposite edge portions of the plate 36 and 55 comparatively wide guides 41 are carried by the spacers 40. The guides 41 are in spaced parallel relation to the plate 36 and provide channels for guiding the opposite longitudinal edge portions of the toweling T. A rolled edge portion or guide 60 42 is provided on the upper end of the element 12 to guide and change the direction of movement of the toweling T. The toweling T is brought upwardly from the forward face of the supply roll 11 and is trained over the guide 42 to pass downwardly across the forward face of the plate 36. The guides 41 operate to hold the toweling T in 65 its proper position against or adjacent the front of the plate 36 and guide it for removal through the opening 35. The pivoted towel guiding and carrying element 12 may be moved or pivoted inwardly by pushing on the toweling T through the opening 29 to release the means 13. The element 12 may be pivoted inwardly in this manner until the plate 36 contacts the forward edge portions 70 28 of the plates 24.

The means 13 is provided primarily to cooperate with the toweling T to limit its withdrawal at each operation of the device. The means 13 also normally holds the toweling T against withdrawal and conceals the lower portion of the toweling T at the opening 30 whereby the users cannot pull on the toweling without first releasing the means 13 by pressing inwardly on the element 12 through the medium of the toweling exposed at the opening 29.

10 The means 13 includes two lever members or levers 43 arranged in the case 10 behind the element 12, each lever having two downwardly projecting arms 44. Forwardly projecting fingers 45 are provided on the lower ends of the arms 44 to 15 cooperate with or extend through the openings 33 in the toweling T. The fingers 45 are preferably inclined upwardly and outwardly and are formed and spaced to readily project into the openings 33 without undesirable interference with 20 the toweling T. Horizontal pivot pins 46 are carried in openings in the plates 24 and ears 47 on the flange 21 and extend through openings in the upper portions of the lever arms 44 to pivotally support the levers 43. Transverse webs 48 25 extend between and connect the two arms 44 of each lever 43. Slots or openings 49 are provided in the plate 36 and the guides 41 to freely pass the fingers 45 so that the fingers may cooperate with the toweling and enter the openings 33 in 30 the toweling. Each lever 43 has an upper rearwardly projecting arm 50. The arms 50 are of sufficient weight to pivot or tend to pivot the levers 43 to move their fingers 45 forwardly 35 against the toweling T and through the openings 33.

When the parts are in their normal positions as illustrated in Fig. 3 of the drawings the fingers 45 extend through the openings or slots 49 at the lower edge of the strip of toweling T directly in the path of the toweling. Operative connections are provided between the element 12 and the levers 43 whereby the fingers 45 are retracted from the openings 49 when the user engages the toweling T through the opening 29 45 and pushes or pivots the element 12 inwardly. The operative connections between the element 12 and the levers 43 include bell cranks positioned at the outer sides of the plates 24 and pivotally mounted on the back 15 at 51. Each of these 50 bell cranks has a forwardly projecting lower arm 52 and an upwardly projecting arm 53. Links 54 connect the upper bell crank arms 53 with the element 12. Pivot pins 55 may pivotally connect the rear ends of the links 54 with the arms 53 55 while pivot pins 56 may pivotally connect the forward ends of the links with the upper end portion of the element 12. The lower forwardly projecting arms 52 of the bell cranks are of sufficient weight to normally hold the element 12 in 60 its normal position illustrated in Fig. 3 of the drawings and operate through gravity to return the element to this position upon the bell cranks being released for return movement, as will be hereinafter described. Laterally projecting lugs 65 57 are provided on the lever arms 50 to be engageable by the bell crank arms 52. Upon a person pushing on the toweling T through the opening 29 the element 12 is pivoted inwardly causing the bell crank arms 52 to pivot upwardly and the 70 engagement of the arms with the lugs 57 causes the levers 43 to pivot in a direction to withdraw the fingers 45 rearwardly out of the path of downward movement of the toweling to the opening 35.

The means 13 includes a door or shutter 58 for normally preventing the user from engaging the lower edge portion of the toweling T at the opening 30. The shutter 58 is guided for vertical movement by slots or grooves 59 in the flange 32. Forwardly projecting fingers 60 are provided on the outer ends of the bell crank arms 52 to carry the shutter 58. The upper end of the shutter 58 is suitably pivotally connected with the fingers 60 as 10 at 61. It will be understood that when the element 12 is pushed inwardly as described above the shutter 58 is raised upwardly out of the opening 30 simultaneously with the retraction of the fingers 45 from the path of the toweling T so 15 that the user may readily engage the lower edge portion of the toweling T and pull it downwardly to withdraw a length of toweling. When the user removes the inward pressure from the element 12 and pulls the toweling T downwardly from the 20 case 10 the heavy arms 52 of the bell cranks return the element to its normal position and allow the arms 50 to operate through gravity to urge the fingers 45 forwardly against the downwardly moving toweling so that the fingers are urged 25 to enter the openings 33 at the upper end of the portion of toweling being withdrawn. The fingers 45 thus operate to limit or stop the withdrawal of toweling from the case 10 and the user may then cut or tear free the withdrawn portion 30 of toweling by subjecting it to a downward pull.

Means may be provided in connection with the levers 43 to insure the straight horizontal or transverse tearing of the paper toweling. Transverse members 63 are attached to the webs 48 and 35 project forwardly so that their forward edges engage the inner side of the toweling when the fingers 45 project through the openings 33. Openings or slots 63^a are provided in the plate 36 to freely pass the forward portions of the members 63. The forward edges of the members 63 may be suitably serrated or sharpened and engage the toweling at or adjacent the slits or cuts 34. The horizontal sharpened edges of the members 63 bearing outwardly against the toweling T 40 cause the toweling to be cut or torn free along horizontal lines between the spaced cuts 34 and between the outer openings 33 and the opposite longitudinal edges of the toweling.

The means 14 is provided to prevent a second 50 or repeated release of the means 13 before the withdrawn portion of toweling T is cut or torn free. The means 14 is in the nature of an interlock or latch means which is released by tearing or cutting free the withdrawn portion of toweling 55 to free the means 13 for further operation. The means 14 includes a latching or interlocking lever 64 pivotally supported on each pivot pin 46. The levers 64 are controlled or actuated through their cooperation with the toweling T and each includes a downwardly projecting arm 65 provided 60 at its lower end with a downwardly and forwardly inclined finger 66. Openings or slots 67 are provided in the plate 36 and the guides 41 to pass the fingers 66 with suitable clearance. The fingers 66 project below the fingers 45 and their forward ends are rounded to properly cooperate with the toweling T as it is being withdrawn through the opening 35.

The lever arms 65 in the particular structure 70 illustrated in the drawings are spaced some distance inwardly from the plates 24 and webs 67^a extend from the lever arms to points beyond the plates 24. Upwardly projecting latch arms 68 are provided on the webs 67^a at the outer sides of the plates 24. The pivot pins 46 extend through

openings in the latch arms 68 to aid in pivotally supporting the levers 64. Springs 69 are connected with the latch arms 68 to normally urge the fingers 66 forwardly into the path of downward travel of the toweling T. A rearwardly projecting latch nose or lug 70 is provided on each arm 68. Lateral lugs 71 are provided on the forward end portions of the bell crank arms 52 to cooperate with the latch lugs 70 when the element 12 is pushed inwardly as described above. The springs 69 yield to allow the lugs 71 to snap or pass over the latch lugs 70 to positions where the latch lugs hold the bell cranks in their up positions and the element 12 in its innermost position. Fig. 4 of the drawings illustrates the lugs 71 cooperating with the latch lugs 70 to releasably hold the element 12 in its inner position and the bell cranks in their upper positions. With the parts in the positions illustrated in Fig. 4 of the drawings the user may remove the inward pressure on the element 12 and engage the lower projecting portion of the toweling T to withdraw the toweling from the case. It will be seen from this that the user is only required to employ one hand in releasing the control and withdrawing the towel T. The shutter 58 is held in its up or inoperative position at this time allowing the ready engagement of the toweling at the opening 30. The fingers 66 normally projecting into the path of downward movement of the toweling T 30 are engaged by the toweling and forced inwardly as the user pulls the toweling downwardly. This inward movement of the fingers 66 causes forward swinging of the latch arms 68 and disengagement of the latch lugs 70 from the lugs 71. The heavy lower arms 52 of the bell cranks then cause the bell cranks to return to their normal positions to move the element 12 to its substantially vertical position.

The fingers 66 are urged forwardly and maintained in engagement with the toweling T by the springs 69 and the means 14 operates through this engagement to prevent a second or repeated release of the means 13. The means 14 latches or holds the element 12 against inward movement until the withdrawn portion of the toweling is cut or torn free. Latches 72 are pivotally supported on the pins 46 to depend or hang adjacent the outer sides of the levers 64. The latches 72 are connected with the lever arms 68 to move therewith and to have limited movement with respect thereto. Stops 73 on the arms 68 are engageable by lugs 74 on the latches 72 to limit the rearward movement of the latches with respect to the arms. Springs 76 are arranged 45 under compression between lugs 75 on the latches 72 and the webs 67^a to urge the latches rearwardly with respect to the lever arms. Lateral lugs 77 are provided on the forward end portions of the bell crank arms 52 to cooperate with latch 60 projections 78 on the latches 72. The latch projections 78 have inclined upper edges engageable by the lugs 77 when the bell crank arms 52 are freed for downward swinging.

Upon the disengagement of the latch lugs 70 65 from the lugs 71 the lugs 77 move into engagement with the inclined edges of the lugs 78 to pivot the latches 72 forwardly. In this manner the lugs 77 are latched under the latch lugs 78 in the positions illustrated in Fig. 5 of the drawings. With the parts in this position the bell crank arms 52 are latched in positions where the element 12 is held against movement and the latches 72 and the fingers 66 are held against any appreciably rearward movement. The lugs 75

78 cooperate with the lugs 71 to prevent the inward movement of the element 12 and upward movement of the shutter 58 so that the user is unable to release the control for the second time.

5 Accordingly the user in order to obtain another portion or length of toweling must tear free the first portion which he has withdrawn from the case 10. When the withdrawn portion of toweling is torn free at the openings 33 and cuts 34 the fingers 66 are free to move forwardly under the action of the springs 69. This forward movement of the levers 64 disengages the latch lugs 78 from the lugs 71. With the latch lugs 78 disengaged from the lugs 71 the means 13 of the control C may again be released by pressing inwardly on the element 12 through the medium of the paper toweling exposed at the opening 29.

When the mechanism of the towel cabinet is in its normal condition the parts are in the 20 positions illustrated in Figs. 1 and 3 of the drawings and the lower edge of the strip of toweling T is at or adjacent the fingers 45. The shutter 58 normally conceals and protects the lower edge portion of the strip of toweling T against engagement by the user. To operate the towel cabinet the user pushes or presses inwardly on the element 12 through the medium of the toweling T engageable through the opening 29. This inward movement of the element 12 swings the 25 bell crank arms 52 upwardly, which upward movement of the bell crank arms is accompanied by upward movement of the shutter 58 and inward retraction of the fingers 45 out of the path of downward movement of the toweling T. The lugs 71 cooperate with the latch lugs 70 to latch the bell crank arms 52 in their up positions where the fingers 45 are retracted and the shutter 58 is withdrawn from the opening 30. This exposes the lower edge portion of the strip of toweling T for engagement through the opening 30 and the user may remove the pressure from the element 12 and pull downwardly on the exposed lower portion of the toweling. As the shutter 58 is automatically latched in its up 40 position the user may grasp the lower portion of the toweling T with the hand he employed to press the element 12 inwardly.

As the toweling T is drawn or pulled downwardly through the opening 35 it engages the fingers 66 and moves them inwardly against the action of the springs 69. This inward movement of the fingers 66 results in disengagement of the latch lugs 70 from the lugs 71. With the disengagement of the lugs 70 and 71 the heavy 45 lower arms 52 of the bell cranks pivot downwardly to return the element 12 and the shutter 58 to their normal positions. During the downward pivoting of the bell crank arms 52 the lugs 71 become latched under the latch lugs 78 as illustrated in Fig. 5 of the drawings. The toweling T may be freely withdrawn or pulled downwardly until a series of openings 33 is brought opposite the fingers 45, whereupon the fingers 45 pass into the openings to stop the downward movement of the toweling. The weighted or heavy lever arms 50 urge the fingers 45 forwardly to enter the openings 33. The projected or withdrawn portion of the toweling T may then be torn or cut free by pulling downwardly on it to cause parting or tearing of the paper toweling between the cuts 34 and between the ends of the outer cuts and the longitudinal edges of the toweling. The means 14 makes it necessary for the user to tear or cut free the withdrawn portion of the toweling T before he can again release the means

13. The cooperation of the lugs 71 and 78 positively prevents the inward movement of the element 12 and thus prevents the retraction of the fingers 45 and the upward movement of the shutter 58. When the user tears or cuts free the withdrawn portion of toweling T the fingers 66 are again free to swing forwardly under the action of the springs 69 so that the lugs 78 of the latches 72 are freed from the lugs 71. The control C is then conditioned or reset for further release or actuation.

The towel cabinet provided by this invention is substantially tamper proof and requires that the user tear or cut free the portion of toweling T which he has withdrawn from the case, in order to obtain a second length of toweling. The amount of toweling T obtainable from the case 10 at one operation is limited or determined by the spacing of the series of openings 33. The cooperation of the fingers 45 with the openings 33 positively limits the extent of withdrawal of the toweling T at each operation. The means 14 is such that the element 12 cannot be improperly operated and retains the shutter 58 in the position where the toweling above the fingers 45 is protected against engagement by the user. The device may be easily operated to obtain the necessary toweling without engaging any metal or mechanical parts. The control C is released by pressing inwardly on the toweling T accessible through the opening 29. This operation exposes the lower edge portion of the toweling T which may then be engaged to withdraw the length of toweling from the case. The toweling that is engaged by the user through the opening 29 is withdrawn for his own use. The supply 11 of toweling T is properly supported in the case 10 and the toweling is fed through the control C without the employment of gear means or a multiplicity of rollers.

This application relates to devices of the general character described and claimed in the United States Letters Patent Number 2,067,760, granted to me January 12, 1937, on an application filed October 15, 1934, and to devices of the general character described and claimed in my co-pending application Serial Number 746,983, filed October 5, 1934. In the devices which are the subject matters of said Letters Patent and said co-pending application the control elements, movable through manual manipulation of the material being dispensed, are rotatable elements.

Having described only a typical preferred form and application of my invention, I do not wish to be limited or restricted to the specific form and application herein set forth, but wish to reserve to myself any modifications or variations that may appear to those skilled in the art or fall within the scope of the following claims.

Having described my invention, I claim:

1. A towel cabinet including a case for housing a supply of toweling, the case having an opening through which the toweling may be withdrawn and having a second opening exposing a portion of the toweling extending from the supply to the first mentioned opening, and means controlling the withdrawal of toweling from the case including a movable element in the case facing the second opening at the inner side of said portion of toweling and bodily movable inwardly by manually acting on the portion of toweling accessible through the second opening.

2. A device of the character described including a case having two openings, means for carrying a supply of sheet material for removal from

- one of said openings, and means for controlling the withdrawal of the material from the case including means in the case for preventing withdrawal of the material, and an element directly facing the other opening at the inner side of the material extending from the supply and depressible through the medium of the material accessible through the second opening to release the last mentioned means.
- 10 3. A device of the character described including a case for housing a supply of sheet material and having an opening, a movable plate in the case facing the opening, means for guiding the material between the opening and the plate, the 15 plate being movable by pressing against the material accessible through the opening, and means for controlling the withdrawal of the material from the case governed by movement of the plate.
4. A towel cabinet including a case for housing 20 a supply of toweling, the case having an opening, means normally preventing withdrawal of the toweling from the case, an element pivoted in the case to be swung inwardly therein to release said means, means training the toweling over the element at the rear of the opening whereby the toweling on the element may be engaged by the user through the opening for moving the element inwardly, and means governed 25 by cooperation with the toweling for preventing actuation of the element and releasable by tearing free a withdrawn portion of the toweling.
5. A towel cabinet including a case having an 30 opening, a supply of strip paper towel material in the case having longitudinally spaced openings, and a control for governing the withdrawal of the material from the case including a member adapted to cooperate with the openings to limit the withdrawal of the material, an element supported in the case for bodily inward movement therein to shift the member to an inactive 35 position, and means guiding a portion of the material to engage a surface of the element and to be accessible through said opening by the user of the cabinet to move the element.
- 45 6. A towel cabinet including a case, a supply of paper toweling material in the case having longitudinally spaced openings, and a control for governing the withdrawal of the material from the case including a member adapted to cooperate with the openings, a plate supported by the case for movement by the user of the cabinet to shift the member to an inactive position, and means governed 40 by cooperation with the material for holding the member in said inactive position releasable on withdrawal of the material, the last mentioned 45 means including a control part engaged and moved by the toweling when the same is withdrawn.
7. A towel cabinet including a case for a 50 supply of toweling, the case having a first opening, through which a portion of toweling is accessible for engagement by the user, and a second opening through which the toweling may be engaged for withdrawal, a shutter normally preventing engagement of the toweling at the 55 second opening, a control governing the withdrawal of the toweling from the case, and an element operatively connected with the shutter and control movable by acting on the portion of toweling accessible through the first opening to 60 release the control and shift the shutter to a 65

position where the toweling is engageable at the second opening.

8. A towel cabinet including a case for holding a supply of toweling, the case having an opening through which the toweling may be withdrawn and having a second opening, a shutter normally closing the first opening against the engagement of the toweling therein, a member normally in the path of withdrawal of the toweling to prevent its withdrawal, a movable element in the case operatively connected with the shutter and member, and means training the toweling over the element to be engageable by the user through the second opening to move the element for the purpose of retracting the 15 shutter and member.

9. A towel cabinet including a case for holding a supply of toweling, the case having an opening through which the toweling may be withdrawn and having a second opening, releasable means preventing withdrawal of the toweling, a movable plate member within the case adjacent the second opening and operatively connected with said means, and means training the toweling over the plate member to be 20 accessible and engageable by the user through the second opening to move the plate member to release said means.

10. A towel cabinet including a case for holding a supply of toweling, the case having an 30 opening through which the toweling may be withdrawn and having a second opening, releasable means normally preventing withdrawal of the toweling, a member in the case positioned at the second opening and supported for inward 35 movement, an operative connection between the member and said means, and means training the toweling across the face of the member to be accessible through the second opening for inward manual pressure to move the member inwardly to release said means.

11. A device of the character described including a case for housing a supply of sheet material, a wall of the case having an opening, a control element carried by the case for swinging movement toward and away from said wall 45 of the case, means guiding the material across the element at the inner side of the opening whereby the material is accessible through the opening to move the element, and means controlling the withdrawal of material from the 50 case governed by movement of the element.

12. A towel cabinet including a case for housing a supply of toweling, the case having an opening through which the toweling is engageable for withdrawal and a second opening through which the toweling is accessible, a shutter normally preventing such engagement of the toweling at the first mentioned opening, means governing the withdrawal of the toweling from 60 the case, and a member within the case manually movable through the medium of the toweling accessible through said second opening to shift the shutter to a position where the toweling is engageable and to release said means.

13. A towel cabinet including a case, a supply of toweling material in the case having longitudinally spaced openings, and a control for governing the withdrawal of the material from the case including a member adapted to enter 70 the openings to limit the withdrawal of the material, and an element in the case operatively connected with the member and bodily manually movable through the medium of the material to retract the member.

14. In a towel cabinet of the character described, a case having an opening, a continuous supply of paper toweling material in the case provided with longitudinally spaced series of openings, the material being adapted to be withdrawn through the opening, means training the toweling to make a portion thereof engageable by the user, a mechanism in the case for controlling the withdrawal of the material including parts adapted to enter the openings to limit the withdrawal of the material, and a manual control for retracting said parts comprising a control element behind said portion of the toweling bodily movable by manual pressure on the said portion of toweling and operatively connected with said parts.

15. A towel cabinet including a case for a supplying of toweling, the case having a first opening and a second opening through which the toweling may be engaged for withdrawal, a shutter normally preventing engagement of the toweling at the second opening, a control governing the withdrawal of the toweling from the case, the control including a part for engaging the toweling to limit its withdrawal, a movable element in the case operatively connected with the shutter and said part, an element in the case at the rear of the first opening movable to release said part and to shift the shutter, means training the toweling over the forward face of the element whereby the element is movable by acting on the toweling accessible through the first opening to release said part and shift the shutter to a position where the toweling may be engaged for withdrawal, and means governed by cooperation with the toweling holding the part released and the shutter in said position and released upon removal of the toweling.

16. A towel cabinet for dispensing sheet towel material having openings including a case for housing a supply of the material and having an opening through which the material may be withdrawn, releasable means for limiting the withdrawal of the material from the case including parts adapted to penetrate openings in the material to thereby stop movement of the material, a manually movable plate member operable to retract the parts to permit further withdrawal of the material, and means training the material on the plate member to be manually engaged for the operation of the member.

17. A towel cabinet including a case for housing a supply of toweling and having an opening, releasable means for preventing withdrawal of toweling from the case, and means for releasing said means including an element carrying a portion of toweling, means supporting the element for movement bodily inwardly in the case where said portion of toweling is manually engageable through said opening to directly transmit inward manual force and movement to the element,

and an operative connection between said element and the releasable means.

18. A towel cabinet including a case for housing a supply of toweling and having an opening, releasable means for preventing withdrawal of toweling from the case, an element supported in the case to swing inwardly therein, means guiding the material across the element to be manually engageable through said opening for the direct transmission of manual inward pressure and movement to the element, and an operative connection between the element and the first mentioned means whereby said movement of the element releases the first mentioned means.

19. A towel cabinet including a case, a supply of paper toweling material in the case having longitudinally spaced openings, and a control for governing the withdrawal of the material from the case including a member adapted to cooperate with the openings to limit the withdrawal of the material, means normally urging the member to an active position to cooperate with openings, an element supported by the case for movement by the user of the cabinet to shift the member to an inactive position, releasable means for latching the element in its actuated position and the member in its inactive position, and a part engaged and moved by the toweling to release the last mentioned means when the toweling is withdrawn from the case.

20. A towel cabinet including a case for housing a supply of toweling, the case having an access opening and an opening through which the material is engageable for withdrawal, and means governing the withdrawal of toweling from the case including a shutter normally extending across the second mentioned opening to prevent the user from engaging the toweling, an element operatively connected with the shutter and supported by the case for movement, means training the toweling on the element to have a portion accessible to the user through the access opening to move the element and thereby shift the shutter to a position where the material may be engaged through said second mentioned opening, and means engageable by the toweling for holding the shutter in the last named position and releasable on removal of the toweling.

21. A towel cabinet for dispensing sheet towel material having openings including a case for housing a supply of the material and having an opening through which the material may be withdrawn, and releasable means for limiting the withdrawal of the material from the case including a member adapted to penetrate an opening in the material to thereby stop movement of the material, and an element bodily manually movable through the medium of the material to retract the member.
